UNITED STATES PATENT OFFICE

162,931

COMPARTMENTED REFRIGERATOR TRAY

Ethel B. Buckles, Columbia City, Ind.

Application October 19, 1950, Serial No. 12,630

Term of patent 7 years

(Cl. D44—1)

To all whom it may concern:

Be it known that I, Ethel B. Buckles, a citizen of the United States, residing at Columbia City, in the county of Whitley, and State of Indiana, have invented a new, original, and ornamental Design for a Compartmented Refrigerator Tray, of which the following is a specification, reference being had to the accompanying drawing, forming part thereof.

The characteristic features of my design for a compartmented refrigerator tray reside in the projections at the upper corners thereof having the configuration shown.

I claim:

The ornamental design for a compartmented refrigerator tray, as shown and described.

ETHEL B. BUCKLES.
